United States Patent Office.

JOHN R. DAVIS, OF COVINGTON, GEORGIA.

Letters Patent No. 96,783, dated November 16, 1869.

IMPROVEMENT IN GATES.

The Schedule referred to in these Letters Patent and making part of the same.

To all whom it may concern:

Be it known that I, JOHN R. DAVIS, of Covington, in the county of Newton, and State of Georgia, have invented a new and useful Improvement in Self-Supporting Gates; and I do hereby declare that the following is a full, clear, and exact description thereof, which will enable others skilled in the art to make and use the same, reference being had to the accompanying drawings forming part of this specification.

This invention relates to a new and useful improvement in the method of hanging and supporting farm and other gates; and consists in applying a rod diagonally across the gate, the upper end of which rod forms a part of the upper gate-hinge, and is connected with another rod, which forms the other part of the hinge, and passes horizontally through two or more posts, with a lever-nut on its outer end, as herein-after more fully described.

The accompanying sheet of drawing represents a front elevation of a gate, constructed and supported according to my invention.

A B represent the gate-posts.

C is a post of the fence.

D is the gate, which is hung to the post B.

E is the supporting-rod, which is fastened in the lower rail F of the gate, as seen at G, near the front lower angle of the gate, from whence it passes diagonally to the upper back angle, upon the end of which there is an eye for forming half of the upper hinge, as seen at H.

The other half of the upper hinge is formed by an eye on the rod J. This rod passes through the gate-

post B, and extends from thence horizontally to the post C, through which it passes.

K is a lever-nut on the end of this rod, a screw-thread being cut upon it, with which the nut engages.

By extending this rod from the gate-post through one or more posts of the fence, the strength and support of such posts are obtained for supporting the gate, as the rod J draws upon the rod E, which acts directly upon the lower front corner of the gate. Should there be any settling of this corner of the gate, it can be easily drawn into place by turning up the nut K.

L is a washer, between the nut and the post C.

N is the lower hinge, formed by two shank-eyes. This hinge, as well as the fastenings of the gate at O and P, I am aware are old, and consequently form no part of my invention.

This gate swings in either direction with equal facility, and supplies a want which has long been felt by farmers and others; that is, a self-supporting gate.

Having thus described my invention,

I claim as new, and desire to secure by Letters Patent—

In combination with a gate, which swings either in one or both directions, the rods E and J, arranged and operating substantially as and for the purposes herein shown and described.

JOHN R. DAVIS.
